UNITED STATES PATENT OFFICE

JOHN A. KIEDROWSKI, OF CHICAGO, ILLINOIS

FOUNTAIN PEN

Application filed March 21, 1930. Serial No. 437,911.

This invention relates to fountain pens of the type commonly known as self-filling fountain pens.

An object of the invention is to provide a pen of this character which will contain inks of different colors, together with means for adjusting the pen so that any selected color may be used.

To this end, the invention includes a number of separate ink reservoirs and the means to direct the ink from any one of the reservoirs to the point of the pen, means being provided whereby the pen may be quickly and conveniently adjusted for this purpose.

Another object of the invention is the provision of means for filling the ink reservoirs, so that when the ink from any one of these reservoirs becomes exhausted it may be readily replaced.

With the above and other objects in view, the invention further includes the following novel features and details of construction, to be hereinafter more fully described, illustrated in the accompanying drawings and pointed out in the appended claims.

In the drawings:

Figure 1 is an elevation of a fountain pen constructed in accordance with the invention.

Figure 2 is an enlarged fragmentary sectional view on the line 2—2 of Figure 1.

Figures 3, 4 and 5 are enlarged sectional views taken respectively on the lines 3—3, 4—4 and 5—5 of Figure 2.

Figure 6 is an enlarged detailed sectional view of the positioning ring.

Figure 7 is an enlarged sectional view on the line 7—7 of Figure 2.

Figure 8 is an enlarged sectional view on the line 8—8 of Figure 1.

Figure 9 is a fragmentary elevation of one end of the pen with the cap removed.

Figure 10 is a similar view looking at the reverse side from that shown in Figure 9.

Figure 11 is a detailed sectional view on the line 11—11 of Figure 8.

Figures 12 and 13 are enlarged sectional views taken respectively on the lines 12—12 and 13—13 of Figure 8.

Figure 14 is a sectional view on the line 14—14 of Figure 8.

Referring in detail to the drawings wherein like characters of reference denote corresponding parts, the reference character 15 indicates the barrel of the pen which may be constructed of any suitable material. Arranged within the barrel are separate ink reservoirs 16. These reservoirs are made of rubber or of any suitable material and have one of their restricted ends secured over projections 17 provided upon the inner end of a stem 18. Any suitable number of reservoirs 16 may be employed, and as three reservoirs are shown, the inner end of the stem 18 will carry three of the projections 17.

The stem 18 is received within a bore or socket 19 provided in a bar 20 which is fast with the pen point 21.

The stem 18 is provided with separate ink conduits or passages 22 whose inner ends communicate with the reservoirs 16 through the projections 17, as clearly shown in Figure 8 of the drawings. The outer ends of the conduits or passages 22 are adapted to register with a passage 23 provided in the bar 20, and this passage 23 is in communication with the recess 24 which is covered by the pen point, as is usual in fountain pens.

The outer end of the stem 18 is pointed and the inner end of the socket 19 is similarly shaped, and the pointed end of the stem 18 is yieldingly forced in contact with the inner end of the socket by means of a coiled spring 25. This provides a proper fitting of the stem within the socket and proper register between the passages 22 and 23. The spring 25 is retained within the socket by means of a threadedly engaged ring 26.

Fast with the pen point 21 is a sleeve 27. This sleeve is rotatable within a socketed member 28 which is carried by and extends from the barrel 15. The stem 18 passes through the inner end of this socketed member 28 and the sleeve 27 carries at its outer end a knurled flange 29, so as to provide convenient means to rotate the sleeve and consequently rotate the pen point 21 and the bar 20. As shown in Figure 10 of the drawings, the pen point 21 is of the barrel type.

As previously stated, three ink reservoirs 16 are shown. These reservoirs may contain inks of any color, for example red, purple and blue. These colors are indicated upon the extension 28 as shown in Figures 9 and 10 of the drawings. The knurled flange 29 contains an indicating mark 30 and when this mark is brought into register with any one of the arrows 31 upon the extension 28, the passage 23 will be in register with the outer end of one of the passages 22, depending upon the color selected. Ink from the reservoir 16 containing the selected color will then flow from this reservoir through the passages 22 and 23 to the pen point. The pen point may be protected by a cap 32 which has a threaded engagement with the barrel and this cap carries a clip 33, whereby the pen may be retained within the pocket of the user. The clip 33 is provided at its free end with a clothing engaging portion 34, while the inner end of the clip is secured within the cap by means of a sleeve 35.

The ends of the reservoirs 16 remote from the pen point have secured thereto transversely rectangular shafts 36. These shafts are longitudinally slidable in sleeves 37 provided in a bearing member 38 which is threadedly secured in the end of the barrel 15 as shown in Figure 2 of the drawings. The shafts 36 have mounted thereon pinions 39, 40 and 41. These pinions are axially and circumferentially offset and are adapted to be engaged by an internally toothed operating ring gear 42. This gear 42 is axially adjustable and is positioned within a cap 43 at the end of the pen. The gear 42 is provided with radially disposed diametrically located lugs 44 which are received within slots 45 provided in the cap 43. Thus, the gear 42 is permitted independent axial movement, but is rotated when the cap is rotated.

Extending inwardly from the gear 42 are diametrically located pins 46. These pins have one of their ends secured to the gear 42 as shown at 47, while the other ends of the pins are provided with lugs 48 which enter grooves 49 provided in a positioning ring 50. The grooves 49 are inclined as shown in Figure 6 of the drawings and are located upon diametrically opposite sides of the sleeve as shown in Figure 7. The grooves are provided with lands 51, 52 and 53 and when the lugs 48 are positioned within the lands 51, the gear 42 will engage in pinion 39. In this position, rotation of the cap 43 will collapse the reservoir 16 with which the pinion 39 is connected. Air will thus be exhausted from the reservoir and ink will be drawn inward as the reservoir resumes its normal position, as will be readily understood. By rotating the positioning sleeve 50, the lugs 48 will travel through the inclined grooves 49 to the land 52, whereupon the gear 42 will engage 65 the pinion 40 to rotate said pinion and col-

lapse its particular reservoir. Further rotation of the sleeve 50 will position the lugs 48 in the lands 53 so that the gear 42 will engage the pinion 41. Any one of the reservoirs 16 may thus be filled.

The shafts of the pinions 40 and 41 are provided at their ends remote from the reservoirs with bearing members 54.

In order to prevent accidental rotary movement of the pen point, the invention provides a spring dog 54. As shown in Figure 8 of the drawings, one end of this dog enters a groove or recess provided in the sleeve 27 and the other end of this dog is engaged within a groove provided in the projection 28. Three grooves are provided in the projection 28 and these grooves are so positioned as to be engaged by the dog 54 when the pen point is adjusted to any of the three positions for red, purple or blue ink. Due to the resilient connection of the dog 54 it will have a yielding engagement within the groove so that the pen point may be manually rotated for the purpose above set forth.

In order to accurately position the ring gear 42 to fill a particular reservoir, the ring 50 is provided with an indicating mark 55 which is adapted to be brought into register with either the word red, purple or blue provided on the barrel of the pen. In other words when it is desired to fill the red reservoir, the indicator 55 is positioned as shown in Figure 1 so that the ring gear 42 will engage the proper pinion for collapsing the red ink reservoir.

The invention is susceptible of various changes in its form, proportions and minor details of construction and the right is herein reserved to make such changes as properly fall within the scope of the appended claims.

Having described the invention what is claimed is:

1. In a fountain pen, a barrel, a pen point at one end of the barrel, a plurality of collapsible ink reservoirs within the said barrel, selective means to direct ink from any one of the reservoirs to the pen point, means operatively connected with each reservoir to collapse the reservoirs to fill the same, and means common to all of the reservoirs, collapsing means to selectively collapse any one of the reservoirs.
2. In a fountain pen, a barrel, a pen point at one end of the barrel, a plurality of collapsible ink reservoirs within the said barrel, selective means to direct ink from any one of the reservoirs to the pen point, a gear operatively connected with each of the reservoirs to collapse the latter when the gear is rotated, means common to all of said gears to rotate the same, and means to position the gear rotating means to selectively collapse any one of the reservoirs.

3. In a fountain pen, a barrel, a pen point at one end of the barrel, a plurality of collapsible ink reservoirs within the said barrel, selective means to direct ink from any one of the reservoirs to the pen point, a gear operatively connected with each of the reservoirs to collapse the latter when the gear is rotated, an operating gear common to all of said gears, means to engage the operating gear with any one of the reservoir collapsing gears, and means to rotate the operating gear.

4. In a fountain pen, a barrel, a pen point at one end of the barrel, a plurality of collapsible ink reservoirs within the said barrel, selective means to direct ink from any one of the reservoirs to the pen point, relatively offset gears operatively connected with the reservoirs to collapse the latter when the gears are rotated, an operating gear, means to move the operating gear into engagement with any one of the offset gears, and means to rotate the operating gear.

5. In a fountain pen, a barrel, a pen point at one end of the barrel, a plurality of collapsible ink reservoirs within the said barrel, selective means to direct ink from any one of the reservoirs to the pen point, a stem common to all of the reservoirs, said stem having ink passages therein with the inner ends of these passages in communication with the ink reservoirs, a bar rigid with the pen point and having a socket therein to receive the stem, said bar having a passage therein communicating with the pen point and means to mount the bar and pen point for rotation with respect to the stem to bring the bar passage into register with any one of the passages in the stem.

In testimony whereof I affix my signature.
JOHN A. KIEDROWSKI.
